US0D1022714S

(12) **United States Design Patent** (10) Patent No.: **US D1,022,714 S**
(45) Date of Patent: ** Apr. 16, 2024

(54) **WEARABLE DEVICE WITH GRAPHICAL USER INTERFACE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Kevin Will Chen**, Cupertino, CA (US); **Andrew Patrick Clymer**, San Jose, CA (US); **Clara Geneviève Marine Courtaigne**, Palo Alto, CA (US); **Markus Diebel**, San Francisco, CA (US); **Alan C. Dye**, San Francisco, CA (US); **Aurelio Guzmán**, San Jose, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Aaron Mathew Melim**, San Francisco, CA (US); **Marc A. Newson**, London (GB); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Jacob Weiss**, Sunnyvale, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/784,925**

(22) Filed: **May 21, 2021**

(51) LOC (14) Cl. **10-02**

(52) U.S. Cl.

USPC **D10/32; D14/344; D11/3**

(58) **Field of Classification Search**

(57) **CLAIM**

The ornamental design for a wearable device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a wearable device with graphical user interface showing the claimed design;

FIG. 2 is a rear perspective view thereof;

FIG. 3 is a front view thereof;

FIG. 4 is a rear view thereof;

(Continued)

FIG. 5 is a left side view thereof;
 FIG. 6 is a right side view thereof;
 FIG. 7 is a top view thereof; and,
 FIG. 8 is a bottom view thereof.

**1 Claim, 8 Drawing Sheets
 (8 of 8 Drawing Sheet(s) Filed in Color)**
